PROTECTED BLADE

Joseph M. Bowen, West Quincy, Mass., assignor to
 Gillette Safety Razor Company, Boston, Mass.,
 a corporation of Delaware

Application September 17, 1936, Serial No. 101,231

6 Claims. (Cl. 206—46)

This invention relates to the packaging of fine-edged blades, such for example as safety razor blades. In one aspect it consists in a blade protected completely by a novel wrapper of sheet material, and by completely I mean that the blade is fully enclosed at its ends, side edges and faces. In another aspect it consists in a method of protecting blades in that manner by assembling them in a novel manner with a wrapper having slots in certain of its folded-over portions.

In handling safety razor blades under commercial conditions of transportation and distribution and in the more or less casual treatment of such blades by the user, the extremely fine, keen edge of the blade is likely to become dulled by being brought into contact with its wrapping either at a fold vertex or by being drawn across or cutting the wrapper in being removed therefrom. On this account the best and most skillful efforts of the manufacturer in sharpening blades are often brought to naught, because of the damage done to the fragile and delicate structure of the blade edge after it has been brought to the keenest possible shaving condition and before the shaving operation is actually undertaken.

With these conditions in view an important object of the present invention is to provide a novel wrapper in which the blade may be fully enclosed and held positively in such position that its cutting edge is protected from all direct contact with the fold vertex lines of the wrapper. I have discovered that the desired results may be accomplished by slotting the end tabs of the wrapper so that the ends of the blade may be passed through them and so interlocked that transverse shifting of the blade in the wrapper is positively prevented. Then, by folding the side flaps of the wrapper on a line outside the sharp edge or edges of the blade the latter is held positively and at all times out of contact with the fold vertex lines of the wrapper. An important advantage of such a wrapper is that it obviates the use of spots of vaseline which have been relied upon heretofore to attach the blade to its wrapper and thus prevent displacement therein. While such means are effective in general, they are sometimes variably affected by hot weather conditions and it is not always practical to keep automatic machinery as clean as desired when supplemented by a system for delivering melted vaseline.

The method of my invention is characterized by the steps of folding slotted end tabs of a wrapper into upright and parallel relation, en-

tering the opposite ends of the blade into slots therein and then folding or closing the tabs, simultaneously causing the ends of the blade to pass through the slots and become superposed upon the outer faces of the tabs. Preferably and as herein shown, side flaps of the wrapper are then folded to cover the ends of the blades which project through the tabs. An advantage of treating the wrapper in the manner outlined is that each end tab has a square fold extending fully across the wrapper blank so that the whole width thereof may be used in the holder to box up or position the wrapper and its end tabs. Moreover, since the corners of the body of the wrapper are maintained intact, the wrapper itself may be accurately and positively located by pins set at the four corners of the blank.

Preferably the wrapper and blade are assembled by first turning up the end tabs of the blank so that the slots therein are located at substantially the same level, then locating the blade in alignment with the slots and subsequently closing the end tabs and simultaneously lowering the blade to the body of the wrapper with approximately a toggle action.

Both the wrapper and method of my invention may be employed with particular advantage in connection with blades provided with corner notches defining elongated unsharpened end portions in the blade, since by the procedure outlined such a blade will interlock with the wrapper not only in a transverse sense but also in a longitudinal or endwise sense.

These and other features of the invention will be best understood and appreciated from the following description of one manner in which the method may be put into practice as illustrated in the accompanying drawing, in which,—

Fig. 1 is a plan view of the wrapper;

Fig. 2 is a view in perspective of a blade positioned above a partially folded wrapper;

Fig. 3 is a corresponding view in front elevation, the blade and wrapper being shown in section;

Fig. 4 is a plan view of the wrapper with its end tabs closed upon a blade; and

Fig. 5 is a plan view of the wrapper completely closed upon a blade, the latter being shown in dotted lines.

The wrapper blank, which may be made of thin sheet material such as oiled or waxed paper, as shown in Fig. 1, comprises a rectangular body portion 10 scored to define side flaps 11 and 12 and end tabs 13. Each end tab tapers outwardly to a straight end edge and is provided with a

transverse slot 14. The slots are located entirely without or beyond the fold lines of the tabs and have inwardly tapering end edges. The re-entrant angles formed at the juncture of the side flaps 11 and 12 with the end tabs 13 supply convenient points at which the blank may be engaged and positively located for the wrapping operation by spaced pins 18 or the like, such as shown in Fig. 4.

10 In the drawing there is shown for illustration a safety razor blade 15 of the Gillette type having oppositely disposed cutting edges and re-entrant corner recesses 16 which define in the blade elongated unsharpened end portions 17.

15 The blade, or a similar blade, may be presented to the wrapper in automatic machinery by a suction head 20 having nozzles which engage the surface of the blade at spaced points and maintain the blade in position by a vacuum created in the head. The head is moved by mechanism, not shown, to carry one blade after another from a stack in a magazine into position in alignment with and above successive wrappers which may be presented by a rotary turret or other mechanism.

20 The preliminary position of the blade 15 with respect to the wrapper is shown in Figs. 2 and 3. The body of the wrapper 10 and the side flaps 11 and 12 are held flat, or substantially so, while the end tabs 13 are turned into upright and parallel position, as indicated best in dotted lines in Fig. 3. In this condition the slots 14 are brought to the same level and the blade 15 is positioned between and in alignment therewith. While the blade is so held the end tabs are bent simultaneously inwardly by a pair of blades 22 carried respectively in the ends of bell crank levers 21 arranged to swing about horizontal studs 23 and connected together for simultaneous movement by gear segments 24.

25 The preliminary action of the blades 22 is to swing the end tabs 13 inwardly until the end portions 17 of the blade have entered the slots 14 therein. When this has once taken place the blade 15 is quickly lowered upon the face of the wrapper 10 and simultaneously the end tabs 13 are folded inwardly, the movement continuing with a toggle action until the tabs 13 have been brought down into contact with the upper face of the blade 15 and the ends 17 of the blade have passed fully through the slots 14 and lie in contact with the upper face of the tabs. It will be seen that in this operation the end edges of the shoulders formed by the notches 16 in the blade are brought into engagement with the material of the end flaps outside the two ends of the slots 14 and that the longitudinal edges of the shoulders in the blades are interlocked with the end edges of the slots 14. The blade is thus held positively against both transverse or

endwise movement. Subsequently, the side flaps 11 and 12 are folded over the end tabs on fold lines located without or beyond the sharpened edges of the blade and the wrapping operation is thus completed.

Having thus described my invention, I claim as new and desire to secure by Letters Patent:—

1. A safety razor blade having shoulders and unsharpened end portions projecting beyond the shoulders, in combination with a protecting cover 10 having a body portion longer than the blade and end tabs folded on a line parallel to and substantially beneath the ends of the blade, the tabs being slotted whereby the unsharpened ends of the blade may project through the tabs up to the 15 line of its shoulders.

2. A safety razor blade having shoulders and unsharpened end portions projecting beyond the same, in combination with a protecting cover 20 comprising a body portion as long as the blade 20 and end tabs with slots through which said end portions of the blade project, and side flaps arranged to cover the portions of the blade which project outside the end tabs.

3. A protected blade having shouldered end portions, in combination with a wrapper having a body portion as long as the blade and end tabs folded inwardly over the blade on fold lines spaced apart by the full length of the blade, the tabs having slots to receive the end portions of 30 the blade, which slots are located nearer together in the closed wrapper than said fold lines.

4. A safety razor blade having corner notches defining unsharpened end portions, in combination with a wrapper having a body portion as 35 long as the blade and tabs folded coincidently with the end edges of the blade and slotted so that the shoulders of the blade engage the inner face of each tab and the end portions extend through the slots and upon outer faces of the 40 tabs.

5. A safety razor blade having corner notches defining unsharpened end portions, in combination with a wrapper having a body portion as long as the blade and tapering tabs folded coincidently 45 with the end edges of the blade and slotted above their respective fold lines at a height leaving at each end of the slot material substantially equal to the width of a corner notch.

6. A protected blade having a wrapper with a body portion longer than the over-all length of the blade, side flaps, and tabs folded inwardly over both ends of the blade, the tabs being slotted at points beyond their fold-lines and the ends of the blades projecting through the slots in the 55 inwardly folded tabs and being covered by the side flaps.

JOSEPH M. BOWEN.
